UNITED STATES PATENT OFFICE.

CHARLES T. SCHOEN, OF ALLEGHENY, PENNSYLVANIA.

CAR-BOLSTER.

SPECIFICATION forming part of Letters Patent No. 537,076, dated April 9, 1895.

Application filed October 23, 1894. Serial No. 526,742. (No model.)

To all whom it may concern:

Be it known that I, CHARLES T. SCHOEN, a citizen of the United States, residing at Allegheny, in the county of Allegheny and State of Pennsylvania, have invented a certain new and useful Improvement in Bolsters or Transoms, of which the following is a full, clear, and exact description.

The object of this invention is to produce from sheet or plate metal, preferably soft steel, by pressing or otherwise, bolsters or transoms for railway cars and the like.

In practice, I have found that bolsters having straight sides are of barely sufficient rigidity and stiffness to resist the strains incurred under all ordinary circumstances, and very seldom or never capable of resisting such strains under extraordinary conditions; and in a built-up or composite bolster constructed of two main pieces united by tie-pieces, there are necessarily many rivet holes and rivets employed, themselves being elements of weakness in the structure; and the rivets having to be applied hot, additional cost of material and labor thereby are involved. In the manufacture of hot-pressed steel articles, the articles, as a rule, are very much superior in quality and ordinarily less expensive to make, when they are produced of a single piece.

In order to permit car builders to use steel bolsters or transoms interchangeably with those of wood, and also to admit of the use of steel bolsters or transoms on the ordinary Master Car Builders' standard diamond-frame trucks, I provide for the variations in height at the points where the center-bearing plate is applied and where the spring-plates are used, by building up these points with added pieces of metal. Now, with these facts in mind, my invention may be stated to consist of a pressed steel bolster or transom formed integrally with a solid flat face, side flanges and return flanges at their edges, the side flanges being widest at the center of the bolster and decreasing in width toward both ends of the bolster, and pressed steel spacing plates disposed at points thereon necessary to build up such bolster to the required heights for use.

The invention also consists in the peculiar construction of such spacing plates.

In the accompanying drawings illustrating

my invention as applied to a truck bolster or transom for railway cars, in the several figures of which drawings like parts are similarly designated, Figure 1 is a side elevation. Fig. 2 is a top plan view. Fig. 3 is a cross-section at 3—3. Fig. 4 is a cross-section at 4—4, and Fig. 5 is an elevation at the end.

As shown most clearly in Figs. 4 and 5, the truck bolster or transom is made with a flat bearing surface, face or top *a*, side flanges *b*, which are widest at the point of greatest strain and decrease on inclined lines toward opposite ends, and the return flanges *c* at the longitudinal edges of the side flanges, all integral or of one piece of metal. Thus, a hollow, substantially rectangular body is produced, which is open at its bottom, and which is capable of withstanding as well extraordinary as ordinary strain. The return flanges *c* extend, by preference, from end to end. A bolster or transom thus constructed has been demonstrated to meet practically all the requirements of the strains to which it is subjected in use.

The several parts of the body being integral, admit not only of its being produced economically and quickly by the present well-known methods of pressing steel plates, but in addition insures a homogeneity in the article which greatly augments its endurance or capacity.

Wooden bolsters are cut away at their ends for the reception of the arch-bars or straps of diamond frames, thus leaving the middle portion higher than the ends, the center-bearing plate being placed upon the higher level, and in order to enable me to interchange my steel bolsters with such wooden bolsters, or to adapt them to diamond frames, I provide for variations in height by building up the bolsters at the desired point or points by the addition of metal spacing plates of the proper height. Such plates are shown at *d* for the center-bearing plates, and at *e*, *e*, for the spring-plates, the said spring plates themselves not being shown. The spacing-plates *d* are made with end flanges *d'*, by means of which they may be riveted or otherwise fastened to the body, and with an intervening elevated seat *d'* to receive the center-bearing *f*, and this elevated seat is provided with a central transverse depression *d''* to stiffen it and to admit

- of the passage of the king-bolt and for the reception of fastening devices. Obviously, any desired height or elevation of the center-bearing plate may be obtained by using a 5 plate d of proper height. The side-bearings g, g , may be similarly raised, or they themselves may be made of the proper height in the first instance, as may also the center-bearing plates, such manufacture being feasible, 10 in a measure at least, on all Master Car Builders' standard work. The spring-plate additions e, e , similarly are made with end flanges e' for fastening them to the return flanges c , and with the elevated seat e^2 , the edges of 15 which may be provided with pockets e^3 , or a transverse depression, such as that designated d^3 in the plates d , to receive fastening devices. The plates d and e are made by pressing up the same from flat, steel plate. 20 Bolster column-guide plates h are shown as of the construction set forth in my concurrent patent, No. 529,809, granted November 27, 1894. 25 As already indicated, bolsters or transoms may be constructed in accordance with this invention by pressing them up from steel or other plate metal, in a very economical manner, and such beams possess great strength or endurance in meeting both compressive and 30 tensile strains.
- I do not limit my invention to bolsters or transoms for trucks, for obviously it may be used for bodies as well.
- What I claim is—
- 35 1. As an improved article of manufacture, a pressed steel bolster or transom having an

integral solid, flat face, side flanges and return flanges at their edges, the side flanges being widest at the center of the bolster or transom and decreasing in width toward both 40 ends of the bolster or transom, and applied pressed steel spacing plates arranged upon such bolster or transom at points thereon required to be built up to arbitrary standard heights, substantially as described. 45

2. A metal bolster or transom, combined with spacing-plates having end flanges and an intermediate transverse depression, and applied to the bolster or transom to gain proper elevations on the said bolster or transom for 50 the application of usual appurtenances, substantially as described.

3. The spacing-plate herein described, having end flanges, a central depression and an intervening elevated seat, and adapted for 55 use in building up bolsters or transoms and the like for the reception of the center-bearing plate and the spring-plates, substantially as specified.

4. The combination of the bolster or transom, a central spacing-plate, a center-bearing plate applied to such spacing-plate and end spacing-plates for the reception of the spring-plates, the several spacing-plates having end 60 flanges, a central depression and an intermediate elevated seat, substantially as described. 65

In testimony whereof I have hereunto set my hand this 13th day of October, A. D. 1894.

CHARLES T. SCHOEN.
